United States Patent

Des. 235,305
Patented June 10, 1975

235,305

ARTICLE OF FLATWARE

Augusto Salviato, Corso Mario Abbiate, 110,
Vercelli, Italy

Filed June 11, 1973, Ser. No. 369,027

Term of patent 14 years

Int. Cl. D7—03

U.S. Cl. D7—137

FIG. 1 is a top perspective view of an article of flatware showing my new design as embodied in a spoon;

FIG. 2 is a side elevational view thereof;

FIG. 3 is a top plan view thereof;

FIG. 4 is a bottom plan view thereof;

FIG. 5 is a top perspective view of an article of flatware showing my new design as embodied in a fork;

FIG. 6 is a side elevational view of the fork of FIG. 5;

FIG. 7 is a top plan view of the fork of FIG. 5; and

FIG. 8 is a bottom plan view of the fork of FIG. 5.

I claim:

The ornamental design for an article of flatware, as shown and described.
